Primary Examiner — Melody N Brown(74) *Attorney, Agent, or Firm* — James F. Hann; Haynes Beffel & Wolfeld LLP(57) **CLAIM**

The ornamental design for an automotive vehicle exterior, as shown and described.

DESCRIPTION

FIG. 1 is left side, front perspective view of an automotive vehicle exterior showing my new design;

FIG. 2 is a right side, rear perspective view thereof;

FIG. 3 is a left side elevation view thereof;

FIG. 4 is a right side elevation view thereof;

FIG. 5 is a front elevation view thereof;

FIG. 6 is a rear elevation view thereof; and,

FIG. 7 is a top plan view thereof.

The invention is shown together with environmental structure in broken lines in FIGS. 1-6, the environmental structure forming no part of the claimed design.

1 Claim, 6 Drawing Sheets
